United States Patent Office

Des. 203,776
Patented Feb. 15, 1966

203,776

COPYING MACHINE

Chester J. Abend, Camillus, and William A. Morrison,
Solvay, N.Y., assignors to SCM Corporation, New
York, N.Y., a corporation of New York

Filed May 13, 1965, Ser. No. 85,270

Term of patent 14 years

(Cl. D61—1)

FIGURE 1 is a front perspective view of a copying machine showing our new design;

FIGURE 2 is a rear perspective view thereof,

FIGURE 3 is a rear elevational view thereof,

FIGURE 4 is a right hand elevational view thereof,

FIGURE 5 is a top plan view thereof; and

FIGURE 6 is a sectional view taken along line 6-6 of FIGURE 5.

The dominant features of our design are shown in full lines.

We claim:

The ornamental design for a copying machine, substantially as shown and described.
